DIE

Charles M. Brehm, Springfield, Ohio, assignor
to The Steel Products Engineering Company,
Springfield, Ohio, a corporation of Ohio

Application May 26, 1939, Serial No. 275,868

6 Claims. (Cl. 164—47)

This invention relates to apparatus for trimming formed articles, and more particularly to punch and die construction having relatively movable cooperating parts which shift laterally with respect to one another to trim the edges of a partially formed blank.

One object of the invention is the provision of a trimming die of the character mentioned having a cam block, of comparatively small depth, which is slidably carried by a reciprocable pressure plate and arranged to shift laterally while the blank is firmly supported, the cam block and pressure plate being so constructed as to accommodate articles or blanks of comparatively large depth.

Another object of the invention is the provision of a die of the character mentioned including a cam block having cams which control its lateral shifting movement as the cam block is depressed, the lower surfaces of the cams being slidably supported directly on an upwardly projecting portion of a reciprocable pressure plate which is slidably guided for rectilinear movement and which is urged upwardly by yielding cushioning means acting in opposition to the punch.

Other objects and advantages of the invention will be apparent from the following description and the appended claims, taken in connection with the accompanying drawings, in which

30 Fig. 1 is a vertical sectional view through a trimming die embodying the present invention, and showing its relation to a cooperating trimming punch;

35 Fig. 2 is a perspective view of the midportion of a press in which the trimming die and punch are mounted;

40 Fig. 3 is a sectional view showing a portion of the trimming die arranged to receive a blank or shell of comparatively large depth; and

45 Fig. 4 is a section on the line 4—4 of Fig. 1.

Referring more particularly to the drawings, in which a preferred embodiment of the invention has been shown, the apparatus is adapted to trim the edges of a partly formed blank, such as a sheet metal shell, the trimming operation being effected by relatively movable portions of a punch 10 which is carried by the slide or ram 12 of a power press, and a die 11 which is mounted on the press bed.

50 The punch 10 comprises a suitable carrying member 14 having a plate 15 bolted on its lower side. The plate 15 carries a trimming part 16 which is fixed in position by suitable dowel pins. Below the trimming part 16 is a blank clamping member 17, arranged to have lateral shifting

5 movement with respect to the trimming part 16 during the trimming operation. As shown, the clamping member 17 is carried by rods 18 having lower heads received in sockets in member 17 and projecting upwardly through clearance passages in the trimming part 16. The rods extend slidably through thrust plates 20 which rest in suitable pockets in the plate 15. Springs 19 engaged with the thrust plates and with collars fixed on the rods serve to yieldingly hold the member 17 up against the lower flat surface of the trimming part 16 while permitting relative shifting movement of parts 16 and 17.

10 The trimming die 11, which is carried by the bolster plate 22 of the press, comprises a stationary supporting member 23 having an aperture 24 of suitable size to receive a pressure plate 25 and a cam block 26. The pressure plate is slidably guided for reciprocatory rectilinear movement on guide surfaces 27 of the supporting member 23, and slidably supports the cam block 26 for lateral shifting movement during the trimming operation. The cam block 26 comprises a hollow body portion and cams 27 secured thereto as by means of bolts 28. Also secured or bolted to the body portion of the cam block is an upper trimming plate 29, adapted for cooperation with the trimming part 16 of the punch. Fixed to the supporting member 23, at opposite sides of the cam block, are cam members 31 having cam surfaces adapted for cooperation with the cam surfaces provided on the outer sides of the cams 27 which are of such form that as the cam block is lowered by the punch, the cam block will be laterally shifted back and forth, preferably in four different directions, so that the partially formed blank or shell 33 will be trimmed in one stroke of the press as the blank, together with the trimming plate 29 and the clamping member 17 are shifted back and forth with respect to the trimming part 16 of the punch.

15 The depth of the clamping member 17 determines the height of the shearing point with respect to the bottom of the blank so that member 17 functions as a gauge as well as a clamping member for the blank.

20 Extending across the lower side of the body portion of the cam block is a supporting part 34, providing a support for a series of springs 35 which engage, at their upper ends, against a movable ejector plate 36. The part 34, as shown in Fig. 1, is detachably mounted on the lower surface of the body portion of the cam block by means of screws or bolts 37, and projects downwardly from the bottom of the cam block with

the middle portion of the beam arranged a considerable distance below the bottom of the cam block so as to afford a chamber of considerable depth inside of the cam block, for the reception 5 of the blank or shell. The ejector plate 36 carries work clamping members 39 which are located by dowels in fixed position on the plate, the members 39 being suitably formed to clamp against the lower wall of the blank or shell to be 10 trimmed. The blank engaging members are readily removable and replaceable to adapt the die for handling blanks or shells of various forms and different depth.

Normally the ejector plate 36 is held in elevated position by means of the springs 35, its outermost position being determined by stop nuts 40 screwed on studs 42 which project downwardly from the ejector plate. These nuts 40, which are normally held against rotation by suitable 15 positioning dowels 43, are normally engaged in conical sockets 44 provided on the lower side of part 34. As will be apparent from Fig. 1, the ejector plate 36, when depressed by the punch, is approximately at the level of the bottom of 20 the cam block so that when comparatively small blank clamping members 17' and 39' are employed, as shown in Fig. 3, the device is adapted to handle work pieces having a depth substantially equaling or even exceeding the depth of the 25 cam block.

The pressure plate 25 as well as the part 34 is so constructed that its central wall portion is considerably below the bottom of the cam block. The upwardly extending portion of the 30 pressure plate, on which the bottom surfaces of the cams 27 are slidably carried, is guided in the supporting member 23 while the transversely extending wall portion 45 is carried on pins 46 which operate through guide holes in the bolster 35 plate 22. The lower ends of the pins are yieldingly pressed in an upward direction by means of a suitable air or spring cushion. As shown in Fig. 1, the lower ends of the pins rest on a 40 spring pressed plate 47, the lower ends of the 45 springs being supported on stationary beam 48.

In operation, the partially formed blank 33 is placed on the blank clamping members 39, the slide 12 of the press being in its elevated position, and the cam block and the ejector plate also 50 being in their raised positions. The slide 12 then descends, and the clamping member 17 of the punch engages the bottom of the blank and clamps it against the clamping members 39 of the die, the continued descent of the punch then 55 causing the blank to descend in the die as the springs 35 yield to permit this. The parts thus assume the positions shown in Fig. 1 with the peripheral portions of the clamping part 17 of the die extending closely adjacent the inside of 60 the upwardly extending walls of the blank with sufficient clearance therefrom to provide for freely withdrawing and inserting the clamping member within the shell. At this time the lower surface of the trimming part 16 of the punch is 65 substantially flush with the upper surface of the trimming plate 29, and pins or lugs 50 which are carried by the plate 15 are engaged with the upper surface of the trimming plate. The continued descent of the punch then forces the cam 70 block downwardly in the supporting member 23 against the action of the pressure plate 25, and as the cam block descends it is caused to shift laterally first in one direction and then another, to move the blank with respect to the 75 trimming part 16 and trim the edges of the

blank by the time the punch reaches its lowermost position. As the punch is raised by the continued operation of the press, the cam block moves upwardly with it, sliding on the pressure plate and shifting back and forth again until the 10 position of the parts shown in Fig. 1 again obtains. As the punch continues upwardly, the clamping member 17 moves upwardly, permitting the springs 35 to return the ejector plate to its normal position, thus raising the upper portion 15 of the trimmed shell out of the trimming plate 29 to a position from which the shell can be readily removed. During the operation sufficient lubrication is afforded between the cams and the pressure plate from oil which is supplied 20 to the cams, since the cam block is slidably supported on a surface which is at the level of the bottom of the cams 27.

While the form of apparatus herein described constitutes a preferred embodiment of the invention, it is to be understood that the invention is not limited to this precise form of apparatus, and that changes may be made therein without departing from the scope of the invention which is defined in the appended claims. 25

What is claimed is:

1. A die adapted for cooperation with a trimming punch, comprising supporting means having an aperture, cam members fixed on said supporting means, a cam block operable in and movable axially of said aperture and having cams engaging said cam members for laterally shifting the block as the block moves along the aperture, a blank clamping member arranged below the top of the cam block and shiftable laterally with the block and the blank for holding the blank during the trimming operation, yielding means urging said clamping member outwardly, a reciprocable pressure plate having sliding engagement with the cams of the cam block and 30 providing for lateral shifting of the cam block thereon during the trimming operation, said plate having an upwardly extending peripheral wall slidably supporting said cams and slidably mounted in said supporting means and having a bottom wall spaced substantially below the bottom of the cams. 35

2. A die adapted for cooperation with a trimming punch, comprising supporting means having an aperture, cam members fixed on said supporting means, a cam block operable in and movable axially of said aperture and having cams engaging said cam members for laterally shifting the block as the block moves along the aperture, a blank clamping member arranged below the top of the cam block and adapted for cooperation with the punch to hold the blank during the trimming operation, a supporting part detachably secured to and extending across one end of the cam block, yielding means carried by 40 said supporting part and urging said clamping member outwardly, said blank clamping member, said supporting part, and said yieldable means being shiftable laterally with the cam block and relatively stationary with respect to the blank 45 during the trimming operation, and a reciprocable pressure plate on which the cam block is slidably supported for lateral shifting movement during the trimming operation. 50

3. A die adapted for cooperation with a trimming punch, comprising supporting means having an aperture, cam members fixed on said supporting means, a cam block operable in and movable axially of said aperture and having cams engaging said cam members for laterally shift- 55

75

ing the block as the block moves along the aperture, a blank clamping member arranged below the top of the cam block and adapted for cooperation with the punch to hold the blank during the trimming operation, a supporting part secured to and extending across one end of the cam block, yielding means carried by said supporting part for urging said clamping member outwardly, said blank clamping member, said supporting part, and said yieldable means being shiftable laterally with the cam block and relatively stationary with respect to the blank during the trimming operation, a reciprocable pressure plate on which the cam block is slidably supported for lateral shifting movements during the trimming operation, said supporting means slidably guiding said pressure plate for reciprocatory movement, and means exerting an upward pressure on said pressure plate, the inner portions of said supporting part and of said pressure plate being depressed substantially below the bottom of the cam block to provide for the reception of blanks of widely differing heights.

4. A die adapted for cooperation with a trimming punch, comprising supporting means having an aperture, cam members fixed on said supporting means, a cam block operable in and movable axially of said aperture and having cams engaging said cam members for laterally shifting the block as the block moves along the aperture, the lower end of the block being substantially at the level of the lower end of the cams, a blank clamping member arranged within the cam block and adapted for cooperation with the punch to hold the blank during the trimming operation, yielding means urging said clamping member outwardly, said clamping member and said yielding means being shiftable laterally with the cam block and relatively stationary with respect to the blank during the trimming operation, a reciprocable pressure plate slidably guided in said supporting means and having sliding engagement with the cam block to provide for lateral shifting of the cam block thereon during the trimming operation, said plate having a depressed central wall portion located substantially below the surface on which the cam block is slidably engaged.

5. In combination, a trimming punch having a trimming portion and a laterally shiftable blank clamping portion, and a die adapted for cooperation with said trimming punch, said die comprising supporting means having an aperture, cam members fixed on said supporting means, a cam block operable in and movable axially of said aperture and having cams engaging said cam members for laterally shifting the block as the block is moved along the aperture by the trimming punch, a blank clamping member arranged within the cam block cooperating with the clamping portion of the punch to hold the blank

during the trimming operation, a supporting part fixed to and extending across the lower end of the cam block, yielding means carried by said supporting part for urging the clamping member of the die towards the clamping portion of the punch, said blank clamping member, said supporting part, and said yielding means being shiftable laterally with the cam block and relatively stationary with respect to the blank during the trimming operation, a reciprocable pressure plate slidably guided in said supporting means and having sliding engagement with the cams of the cam block at a point substantially even with the lower end of the cam block and providing for lateral shifting of the cam block thereon during the trimming operation, said plate having a depressed central wall portion, and cushioning means engaging said depressed wall portion and yieldingly exerting an upward pressure on the plate.

6. In combination, a trimming punch having a reciprocable plate, pressure members carried by said plate, a trimming portion fastened to the plate, a blank clamping portion, yieldable means for attaching said blank clamping portion to said plate for reciprocating movement therewith and providing for lateral shifting thereof relative to the plate from an initial central position, and a die adapted for cooperation with said trimming punch, said die comprising supporting means having an aperture, cam members fixed on said supporting means, a cam block operable in and movable axially of said aperture under the action of said pressure members and having cams engaging said cam members for laterally shifting the block as the block is moved along the aperture, a blank clamping member arranged within the cam block cooperating with the clamping portion of the punch to hold the blank during the trimming operation, a supporting part fixed to and extending across the lower end of the cam block, yielding means carried by said supporting part for urging the clamping member of the die toward the clamping portion of the punch, said blank clamping portion and said blank clamping member being shiftable laterally with the cam block and being relatively stationary with respect to the blank during the trimming operation, a reciprocable pressure plate slidably guided in said supporting means and having sliding engagement with the cams of the cam block providing for lateral shifting of the cam block thereon during the trimming operation, said pressure plate having a depressed central wall portion to provide for the reception of blanks of widely differing heights, and cushioning means engaging said depressed wall portion and yieldingly exerting an upward pressure on said pressure plate.

CHARLES M. BREHM. 60
